UNITED STATES PATENT OFFICE

CHARLES G. RICHARDSON, OF SPRINGFIELD, VERMONT, ASSIGNOR TO PARKS & WOOLSON MACHINE COMPANY, OF SPRINGFIELD, VERMONT, A CORPORATION OF VERMONT

UNWINDING REEL FOR CLOTH-WINDING MACHINES

Application filed April 5, 1926. Serial No. 99,742.

This invention relates to cloth-winding machines in which bolts or packages of cloth are placed in the machine for measuring or for re-winding into another package, and is intended to provide a simple and convenient construction for mounting and rotatably supporting a bolt of cloth for the unwinding part of the operation.

Bolts of cloth are commonly wound on a thin, flat core-board of wood, paste-board or the like, and oftentimes this core-board has not sufficient stiffness or rigidity to support the endwise grip of chuck jaws that have been heretofore used in this class of devices. Furthermore, oftentimes bolts of cloth are put up without any permanent core-board so that there is no core-board to be gripped by the gripping jaws of a holding chuck. It has also been proposed to insert, lengthwise through the cloth-bolt, a longitudinal shaft or rod carrying fins or webs at each end, but such devices require not only great care in making the insertion but even then are very likely to tear and injure delicate fabrics.

With the object of overcoming these difficulties the present invention comprises a pair of entirely separate aligned stub-shafts held in fixed position at any desired distances apart, and carrying at their inner ends freely rotatable cloth-bolt engaging and supporting members comprising thin, triangular blades, each converging to an apex at its inner end so as to taper to a thin point which are easily inserted between the core-board and the cloth wound thereon up to a point where the diverging side edges engage the inside layer of cloth.

These and other features of this invention will be particularly explained in the following specification and will be described in the claims hereto annexed.

While this unwinding reel is adapted for use in re-winding machines, cloth-measuring machines and the like, it will suffice, for an understanding of the invention, to show the same mounted in a separate frame or horse, sometimes used with such machines, instead of showing the frame of a cloth-measuring

and re-winding machine, as any kind of a frame-support will suffice for the purpose.

In the accompanying drawings I have illustrated a complete embodiment of this improvement, in which:

55

Figure 1 is a front elevation of the complete reel arranged in position to support a bolt of cloth for unwinding.

60

Figure 2 is an enlarged detail view showing one of the cloth-supporting members on the end of its supporting stub-shaft.

Figure 3 is a cross sectional view through the jointed connection between the cloth-engaging and supporting member and the bearing member that is rotatably supported on the stub-shaft.

65

Figure 4 is a cross-sectional view on the dotted line plane of Figure 2.

70

Figure 5 is a detail, in side elevation, showing the construction of the blade member which engages the cloth.

75

In the practice of my invention, according to the form illustrated in the drawings, a pair of completely separated axially adjustable stub-shafts 3 are mounted in aligned bearing bosses 2^a, carried by the up-rights 2 of the frame 1. To bring these coaxially aligned stub-shafts 3 nearer together or farther apart, one or both of the horizontally bored bosses 2^a are provided with set-screws 4 to hold the stub-shafts at different distances apart to accommodate cloth bolts of different widths.

80

On the inner end of each stationary stub-shaft are mounted cloth-bolt engaging and supporting members which are freely rotatable on the inner ends of the stub-shaft. The rotary bearing member 5, mounted on the stub-shaft, in the present instance, is made to permit disconnection of the bolt-engaging members so as to allow the use of different sizes and shapes of bolt-engaging heads.

85

To this end the bearing member 5, comprises an open sleeve or frame, inside of which are mounted axially aligned ball-bearing races 7, fitting around the reduced inner end 3^a of each stub-shaft 3, which leaves a shoulder preventing endwise movement of the bearing member outwardly, while a col-

100

lar 8, threaded over the reduced end of the stub-shaft, when the bearing member is assembled thereon, prevents inward axial movement or displacement but without interfering with the free rotation of the bearing member.

At its inner end this bearing member is provided with a socket 5a of any desired configuration to transmit rotation of the tang or shank 6a, which is inserted therein and held against displacement by a set-screw 5b.

The bolt-engaging heads or members 6, that are shown in the drawings, comprise triangular blades 6 having their sides equally converging toward the apex at the inner end, and preferably also tapered transversely to provide a thin point or apex easily insertable inside the cloth-bolt.

Sometimes it may be desired to produce a slight retardation or friction and to provide for such a contingency I have provided the hub or bearing member 5 with an axially extending pivot pin 5c on which are pivotally mounted clamping jaws 9, which may be drawn together into frictional engagement with the stub-shaft to produce any desired degree of friction. A thrust spring 9b tends to yieldingly thrust the arms apart when they are not clamped against the shaft. Of course, it will be understood that this clamping action is very light when used to retard, as no great degree of tension is required at any time. Such clamping jaws also serve to temporarily hold the chuck against rotation when inserting the bolt.

The operation of the device is as follows. The stub-shafts are drawn apart sufficiently to allow the introduction of a bolt between the supporting heads 6, and one end of the bolt is carefully slipped over the thin apex of one of the heads and gently pushed along the head until it reaches that point where the divergent side edges engage the inner fold of the cloth. The opposite head is then drawn in and inserted point foremost, into the opposite end of the bolt until the distance between its divergent side edges equals the full width of the core. The set screws 4 are then turned down to hold the reel members in this position for unwinding, which operation is due to the pulling of the cloth by the measuring drum or winding reel, with which this device is associated, the full width of the cloth acting like a belt to rotate the independently rotatable bolt-engaging and supporting heads.

Bolts of the most delicate fabrics can be easily and safely mounted upon a reel having this construction without damage or injury to the fabric.

What I claim is:

1. An unwinding reel for a cloth winding machine embracing in its construction a pair of separated axially aligned stub shafts mounted in a supporting frame, means for

holding said shafts stationary at different distances apart, independent cloth-bolt supporting members provided with interior ball-bearings rotatably supported on the inner ends of the aligned stub shafts, and means for preventing axial displacement of said bolt-supporting members while permitting them to rotate freely on the shaft. 70

2. A rotary head for the unwinding reel of a cloth winder embracing in its construction a shaft-encircling bearing member, internal anti-friction bearing elements coaxially aligned therein and spaced apart to afford freely rotatable support on said shaft, and a cloth-bolt engaging and supporting member fixed on the inner end of said bearing member, and means for preventing axial displacement of the bearing member on the shaft. 75

3. A rotary head for a cloth-unwinding reel embracing in its construction a shaft-supported bearing member provided with axially spaced interior anti-friction bearing elements for rotatably supporting it on a shaft, and having an endwise socket extension, a cloth-bolt engaging and supporting member detachably secured in said socket extension for support and rotation with the bearing member. 80

4. A rotary head for a cloth unwinding reel embracing in its construction a bearing member adapted to be rotatably supported against endwise movement on a supporting shaft, a cloth-bolt engaging and supporting member secured to one end of said bearing member to rotate therewith, and frictional retarding means fulcrumed on said bearing member to be pressed against the supporting shaft to provide a frictional resistance to the rotation of said head. 95

In witness whereof, I have subscribed the above specification.

CHARLES G. RICHARDSON.
